CLAIM

The ornamental design for a jack and receptacle for attaching a peripheral device to a handheld device, as shown and described.

DESCRIPTION

FIG. 1 is a front elevation view of a jack and receptacle for attaching a peripheral device to a handheld device, with the jack in an up position, showing our new design;

FIG. 2 is a back view thereof;

FIG. 3 is a bottom plan view thereof;

FIG. 4 is a left side elevation view thereof;

FIG. 5 is a front, bottom and left perspective view thereof;

FIG. 6 is a front elevation view of the jack and receptacle for attaching a peripheral device to a handheld device, with the jack in a down position;

FIG. 7 is a back view thereof;

FIG. 8 is a bottom plan view thereof;

FIG. 9 is a left side elevation view thereof;

FIG. 10 is a front, bottom and left side perspective view thereof;

FIG. 11 is a front elevation view of a jack and receptacle for attaching a peripheral device to a handheld device, in a detached configuration; and,

FIG. 12 is a front, bottom and left perspective view thereof.

The broken line showing of the environment is for illustrative purpose only and forms no part of the claimed design.
